United States Patent Office.

FREDERICK A. HASENCLEVER, OF NEW YORK, N. Y.

Design No. 3,207, dated September 22, 1868.

DESIGN FOR A TRADE-MARK.

The Schedule referred to in these Letters Patent and making part of the same.

TO ALL WHOM IT MAY CONCERN:

Be it known that I, FREDERICK A. HASENCLEVER, of the city, county, and State of New York, have invented a new Design for a Trade-Mark, of which the following is a correct description, and which is shown in the accompanying drawings, which make part of this specification.

The design is for a trade-mark on embroidering-cotton. In the centre is an eagle with spread wings, holding in his talons the American shield and a branch of olive-leaves. Beneath it is a fancy scroll, under which the words "Semper idem" appear. Then comes another fancy scroll, and below it the letters "W. S." Over the eagle are nine stars, and over these the words, "Coton à broder." The whole is enclosed by a border, as shown.

I do not confine myself to the color of the different parts of my design, as, for different qualities of cotton, I may use different colors, but the configuration of words, figures, and letters is always the same.

Having thus described my design, what I claim as new, and desire to secure by Letters Patent, is—
The design for a trade-mark, substantially as herein shown and described.

FR. A. HASENCLEVER.
